UNITED STATES PATENT OFFICE.

ADOLPH P. GUSTAFSON, OF CHICAGO, ILLINOIS, ASSIGNOR TO M. SCHULZ COMPANY, OF CHICAGO, ILLINOIS.

SHEET-CONTROLLING MECHANISM.

1,179,827.

Specification of Letters Patent. Patented Apr. 18, 1916.

Application filed February 16, 1915. Serial No. 8,524.

To all whom it may concern:

Be it known that I, ADOLPH P. GUSTAFSON, a citizen of the United States, residing at Chicago, in the county of Cook and State 5 of Illinois, have invented a certain new and useful Improvement in Sheet-Controlling Mechanism, of which the following is a full, clear, concise, and exact description, reference being had to the accompanying drawings, forming a part of this specification.

My invention relates to mechanism for controlling the lateral position of traveling sheets or webs, as for example the traveling music sheets in mechanical piano players, 15 and similar instruments.

One object of the present invention is to provide a simple, practical and effective mechanism for automatically controlling the lateral position of music sheets, especially with a view to maintaining such sheets in a normal or properly tracking position as the sheet advances.

Another object of the invention is to permit a lateral adjustment of the music sheet 20 to permit playing in a different key or for other purposes, and then to secure automatic regulation or control of the music sheet in this new position or adjustment.

Other advantages and objects will appear 30 and be pointed out hereinafter.

Although I have shown the invention applied to a traveling music sheet of a player piano, it will be understood that the invention may be used for other purposes.

In an application filed by me May 19, 1913, Serial No. 768,491, sheet controlling mechanism, I show an arrangement for controlling the lateral movement of traveling music sheets embodying some but not all of 40 the features of the present invention.

In the accompanying drawings Figure 1 is an elevation of an automatic tracking mechanism embodying my present invention; Fig. 2 is an end elevation of the same; Fig. 3 is a front elevation of the left hand end portion of the device as shown in Fig. 1, on an enlarged scale; Figs. 4 and 5 are perspective views or details of construction; Fig. 6 is a horizontal section taken 45 on line 6—6 in Fig. 1; Fig. 7 is a rear elevation of a portion of the device.

Referring to the drawings I show a tracker board 1, (Fig. 1) having the usual ports 2, and music spools 3 and 4 mounted

in a suitable frame having uprights 5 and 6, and a top piece 7, said frame being mounted upon a horizontally disposed supporting board or member 8. At the right hand side of the figure I show suitable mechanism for connecting a sheet propelling motor with either one or the other of the spools 4 and 3 so as to advance or rewind the music sheet. As said mechanism forms no part of my present invention I will not describe the same herein further than to refer to a finger piece or lever 10 mounted upon a slide rod 11 pivotally connected at its right hand end with a lever 12, said lever 12 engaging a clutch 14 by which either a gear wheel 15 or a clutch 16 member 16 may be engaged to make connection with the roll 4 or the roll 3 respectively, by a movement of the finger piece 10 to one side or the other. At the left hand side of the tracker board 1 is a music sheet engaging member 17 shown more fully in Figs. 3 and 5, said member being conveniently constructed with a vertical portion 17^a having an outwardly turned lip 17^b, and having a vertical slot 17^c and a horizontal shank 18 provided with a longitudinally extending slot 18^a. Said member 17 is arranged to slide back and forth in a substantially horizontal manner in a slot in the vertical member 5, the slot 17^c embracing or straddling a portion 20 of said tracker board so as to guide the member 17. The face of the vertical portion 17^a is intended to make contact with the left hand edge of the music sheet as the same is advanced from the roll 3 to the roll 4, the lip 17 serving to allow the music sheet to advance without any possibility of being caught and stopped or torn. A swinging valve block 21 is pivoted at 22 to a swinging support or port member 23 which latter is in turn pivoted at 24 (Fig. 4) to a block 25 on the upright 5. One or more screws 26 (Fig. 1) passes through the slot 18^a in the member 17 and engages the swinging member 21 whereby 90 said member 21 will be swung to the right or to the left according as the member 17 is shifted to one side or the other by the music sheet, the screws 26 permitting an adjustment of the position of the member 17 with reference to the shank 18 of the member 17. The end of the shank 18 is provided with a weight 27 to counterbalance 95 100 105

the weight of the head 17^a and normally swing or hold said member 17 in engagement with the traveling music sheet. The swinging member 21 has its rear face provided with a recess or channel 30, Figs. 5, 4 and 6. The other swinging member 23 is provided with three ports or apertures 31, 32 and 33 (Figs. 3 and 6), which are so located as to cooperate with the channel 30 in the member 21. The recess or channel 30 is adapted to connect the middle port 32 with either end port 31 or 33 when the member 21 is adjusted to one side or the other.

15 Tubes or pipes 34, 35 and 36 are connected respectively with the ports 31, 32 and 33. The tube 35 runs to a suitable source of pressure reduction, as for example a vacuum chest or the bellows. The tubes 34 and 36 run to two pneumatics 37 and 38, the tube 34 running to the pneumatic 37 and the tube 36 running to the pneumatic 38. These two pneumatics 37 and 38 are mounted upon a block or support 39 on the board 8, and are connected by a link 40 so as to move in unison. The pneumatic 38 is connected by a link 40 so as to move in unison. The pneumatic 38 is connected by a link 41 with a slide rod 42 which latter extends through the uprights 5 and 6 and has a bent end portion 43 provided with a flat end 44, the end portion 43 extending upwardly and forwardly so that the flat end 44 is opposite and in contact with the projecting end 45 of the spindle 46 carrying the music roll 3. The connection between the link 41 and rod 42 is made by means of a screw 41^a passing through the link 41 and engaging a nut 42^a on the threaded end of the rod 42 (Fig. 6), 40 whereby adjustment may be made in the connection between the pneumatics 37 and 38 and the rod 42 and associated parts for moving the music rolls. A rod or link 45 (Fig. 2) extends down from the rod 42 to 45 the spindle 46 of the take-up roll 4, the connection between the rods 42 and 45 being adjustable by means of the screw 45^a, and the connection between the rod 45 and spindle 46 being adjustable by means of the collars 46^a. The other end 47 of the spindle 46 is provided with a projection or feather 48 arranged to slide in a slot 49 in the shaft 49^a which carries the gear 15. By this means the rolls 3 and 4 may be moved in unison 55 in either direction.

50 A rod or lever 50 is secured as by screws 51 to the side of the swinging member 23 and the lower end of this rod 50 is connected with a slide rod 52 which extends horizontally to a swinging finger piece 53 with which said rod 52 pivotally is connected. The connection between the arm 50 and the rod 52 is made adjustable as by passing the rod 52 through a pin 54 at the lower end 65 of the arm 50 and engaging the same by

means of a screw 55. Thus by shifting the finger piece 53 the arm 50 and thereby the valve member 23 may be swung to one side or the other so as to shift the ports in the member 23 with reference to the recess 30 70 in the member 21.

A pneumatic 56 is mounted upon the side of the upright 5 and the member 21 is provided with a finger 57 adapted to engage the upper end of the swinging leaf of the pneumatic 56. Thus when said pneumatic is expanded as shown in Fig. 1, the finger 57 is moved so as to swing the member 21 to the left (Fig. 1), and when said pneumatic is collapsed said member 21 by reason of the 80 weight 27 swings to the right so that the member 17 may engage the side edge of the music sheet. Thus the apparatus may be thrown into and out of operating condition by means of the pneumatic 56. 85

The operation of the apparatus is as follows: When a music sheet is ready to be advanced and the wind inducing apparatus is put into operation, the pneumatic 56 is collapsed, it being understood that said pneumatic is connected with the wind inducing apparatus so as to exhaust said pneumatic when said apparatus is put into operation so as to produce a reduced air pressure for playing purposes. When the pneumatic 56 95 is collapsed the member 17 moves to the right (Fig. 1), and engages the edge of the traveling music sheet. As said sheet moves forward its movement to one side or the other will cause slight movements of the 100 member 17 to one side or the other, movement of said member 17 to the left being made positively by the pushing action of the music sheet, and movement to the right being caused by the weight 27. When this 105 shifting movement of the member 17 occurs, the recess 30 in the swinging member 21 is caused to connect the central port 32 with one or the other of the ports 31 and 33. When this occurs one or the other of 110 the pneumatics 37 and 38 is partially deflated so as to cause a compensating movement of the spools 3 and 4 so as to automatically return the same to normal position. When it is desired to change the key 115 in which the music plays, or to secure a better trackage of the music sheet, that is a better registration of the music sheet apertures with the tracker board ports, or other result, the finger piece or lever 53 is 120 moved in one direction or the other, and when this is done the swinging member 23 is also swung in one direction or the other, with the result that the member 21 is also 125 swung in a corresponding direction and to a corresponding extent, this being due to the pneumatic action as between the recess or channel 30 and the ports 34, 35 and 36, there being continuous suction through the tube 35 tending to create a vacuum in the 130

channel 30 causing a tendency on the part of the members 21 and 23 to adhere to one another and this tendency is sufficient to cause the member 21 to follow the sidewise movements of the member 23. In this way suitable adjustment of the music sheet may be brought about and automatic regulation or control of the music sheet's lateral position will take place with the music sheet in this new position.

It will be understood that changes and modifications may be made without departing from the spirit of the invention.

What I claim is:

15. 1. Means for automatically controlling the lateral position of the music sheet, said means having a pair of adjustable swinging valve members one of said members being adjustably mounted upon the other, thereby 20 permitting adjustment to secure automatic regulation or control of the music sheet in different lateral positions.

25. 2. Means for automatically controlling the lateral position of a traveling music sheet, said means having a pair of adjustable swinging valve members one of said members being pivotally mounted upon the other for permitting control of the music sheet in different lateral positions, and 30 means for manually adjusting said members.

35. 3. The combination of pneumatic means for effecting a relative adjustment between the tracker board and both ends of the music sheet, valve mechanism controlling said pneumatic means and involving two members one mounted for bodily movement and the other mounted upon the first mentioned member and adjustable relatively 40 thereto, and a sheet actuated device controlling said valve mechanism, said valve mechanism being bodily adjustable to preserve its operative condition when said sheet actuated device has its position 45 changed by a change in the lateral position of the music sheet.

40. 4. The combination of pneumatic means for effecting a relative adjustment as between both ends of the music sheet and tracker board, said mechanism comprising pneumatics and connections adapted to effect said relative adjustment, valve mechanism for controlling the operation of said pneumatics and involving two members one 45 mounted for bodily movement and the other mounted upon the first mentioned member and adjustable relatively thereto, and a sheet actuated device controlling said valve mechanism, said valve mechanism being bodily adjustable to permit its operation by said sheet actuated device when the latter is shifted by a change in the lateral position of the music sheet.

55. 5. The combination with pneumatic means for effecting a relative adjustment

between both ends of the music sheet and tracker board in a direction laterally of the music sheet, said mechanism comprising a pair of pneumatics and connections therewith, valve mechanism for controlling said pneumatics, said valve mechanism comprising a port member having ports from which connections extend to said pneumatics, said port member being bodily movable, a swinging valve member mounted upon said port member and having a recess coöperating with said ports, and a sheet actuated member connected with said valve member.

6. The combination of pneumatic means for effecting a relative adjustment as between both ends of the music sheet and tracker board, said mechanism comprising pneumatics and connections adapted to effect said relative adjustment, valve mechanism for controlling the operation of said pneumatics and involving two members one mounted for bodily movement and the other mounted upon the first mentioned member and adjustable relatively thereto, and a sheet actuated device controlling said valve mechanism, said valve mechanism being bodily adjustable to permit its operation by said sheet actuated device when the latter is shifted by a change in the lateral position of the music sheet, and means for adjusting said valve mechanism.

7. The combination with pneumatic means for effecting a relative adjustment between the music sheet and tracker board in a direction laterally of the music sheet, said mechanism comprising a pair of pneumatics and connections therewith, valve mechanism for controlling said pneumatics, said valve mechanism comprising a port member having ports from which connections extend to said pneumatics, said port member being bodily movable, a swinging valve member mounted upon said port member and having a recess coöperating with said ports and normally in connection with one of said ports, and a sheet actuated member connected with said valve member, and means for adjusting said port member.

8. The combination with pneumatic means for effecting a relative adjustment between the music sheet and tracker board in a direction laterally of the music sheet, said mechanism comprising a pair of pneumatics and connections therewith, valve mechanism for controlling said pneumatics, said valve mechanism comprising a port member having ports from which connections extend to said pneumatics, said port member being bodily movable, a swinging valve member mounted upon said port member and having a recess coöperating with said ports and normally in connection with one of said ports, and a sheet actuated member connected with said valve member,

- and means for adjusting said port member, said means comprising a finger piece and connections between the same and said port member.
- 5 9. The combination of means for effecting a lateral adjustment of the music sheet and tracker board, said means comprising a pair of pneumatics and connections therefor, valve mechanism comprising a pivotally mounted swinging port member having ports from which connections extend to said pneumatics, a valve member pivotally mounted upon said port member and having a recess coöperating with said ports, a sheet actuated device having a contact surface adapted to coöperate with an edge of the music sheet, said device being connected with said valve member, a rod attached to said swinging port member, a link connected 10 with said rod and a finger piece connected with said link to permit movement of the same and adjustment of said port member.
- 15 10. The combination of a sheet actuated member, a valve device with which said member is adjustably connected and a port member upon which said valve member is mounted, said port member being mounted for bodily movement and controlling both ends of the music sheet.
- 20 11. The combination of a sheet actuated member, a valve device with which said member is connected and a port member having a plurality of ports upon which said valve member is mounted, a recess provided 25 in said valve member constructed to connect a pair of said ports together, said port member being pivotally mounted so as to permit swinging movement of the same, carrying said valve member with it.
- 25 12. The combination of the music carrying rolls having their spindles mounted to permit longitudinal movement of said rolls, mechanical connections with said rolls for shifting the same longitudinally, a pair of pneumatics link connected together and having a connection with said shifting means, a pivotally mounted port member provided with ports from which tubular connections extend to said pneumatics, a 30 valve member pivotally mounted upon said port member and a sheet actuated device connected with said valve member to shift
- 35

the same when said device is shifted by lateral displacements of the music sheet.

13. The combination of the music carrying rolls having their spindles mounted to permit longitudinal movement of said rolls, mechanical connections with said rolls for shifting the same longitudinally, a pair of pneumatics link connected together and 55 having a connection with said shifting means, a pivotally mounted port member provided with ports from which tubular connections extend to said pneumatics, a valve member pivotally mounted upon said 60 port member, a sheet actuated device connected with said valve member to shift the same when said device is shifted by lateral displacements of the music sheet, and means for adjusting said pivotally mounted port member comprising a rod secured to said member and extended downwardly therefrom, a link connected with said rod, and a movable finger piece connected with said link for moving the same.

75 14. The combination with the music rolls of a pair of pneumatics connected together, a link 41 connected with one of said pneumatics, a rod 42 pivotally connected with said link 41, said rod 42 having an up-turned 80 end portion 43 provided with a flat end 44 adapted to contact with the end of one of the roll spindles, and a rod 45 connected with the rod 42 and also with the spindle of the other roll.

85 15. The combination with the music rolls of a pair of pneumatics connected together, a link 41 connected with one of said pneumatics, a rod 42 pivotally connected with said link 41, said rod 42 having an up-turned end portion 43 provided with a flat 90 end 44 adapted to contact with the end of one of the roll spindles, and a rod 45 connected with the rod 42 and also with the spindle of the other roll, said last mentioned 95 roll spindle having a slideable connection with its driving shaft.

In witness whereof, I hereunto subscribe my name this 4th day of February, A. D., 1915.

ADOLPH P. GUSTAFSON.
